COMPOSITION ROOFING SHINGLE

Floyd L. Worsham, Anniston, Ala.

Application September 29, 1938, Serial No. 232,425

3 Claims. (Cl. 108—7)

The present invention relates to composition roofing shingles of a type commonly known as asphalt shingles and has for its primary object to provide a shingle construction by means of which the roofing may be laid in four separate and distinct styles, the Dutch lap method, the hexagonal method, the side lap method and the individual method.

In conventional type of shingles the same are usually constructed in such a manner as to be capable of laying the shingles according to a single style and it is therefore necessary for the dealer to maintain separate stocks for each type of shingle desired. It is accordingly an object of the present invention to provide a single shingle structure which is capable of being laid in any of the four styles above referred to.

A further object of the invention is to provide a shingle in which one edge is cut in a predetermined outline whereby certain portions will define guides to determine the extent of overlap of adjacent shingles.

A still further object is to provide an article of this character of simple and practical construction, relatively inexpensive to manufacture and in which the laying of the shingles is accomplished with greater facility.

Other objects and advantages reside in the details of construction as more fully hereinafter described and claimed, reference being had to the accompanying drawings forming part hereof, wherein like numerals refer to like parts throughout, and in which—

Figure 1 is a plan view of the blank from which a pair of the shingles are cut.

Figure 2 is a plan view showing the shingles laid according to the side lap method.

Figure 3 is a similar view showing the shingles laid according to the hexagonal method.

Figure 4 is a similar view showing the shingles laid according to the individual method, and

Figure 5 is a similar view showing the shingles laid according to the Dutch lap method.

Referring now to the drawings in detail, and with particular reference to Figure 1 of the drawings, the numeral 5 designates a blank sheet of shingle material, preferably formed of asphalt or other suitable composition, the blank being of substantially rectangular form and cut along a transverse line 6 intermediate its side edges, said transverse cut terminating short of the edges of the blank, the opposite ends of the cut then extending diagonally in opposite directions, as shown at 7 and 8, to provide triangular-shaped extensions 9 at one edge of the shingle while

forming a cutaway corner 10 at the opposite corner of the shingle.

The edge of the shingle formed by the transverse cut 6 is further provided with a relatively short slit 11 extending partly into the triangular tab 9 and terminating in an inclined slit 12 extending inwardly toward the body of the shingle and toward the adjacent edge thereof, the slit terminating in a guide hole 16 sufficiently inwardly from the adjacent edge of the shingle to maintain a suitable connected edge for the tab. The hole 16 also serves to retard tearing of the material along the line of the slit.

The shingle thus formed is capable of being laid in either of the styles or methods illustrated in Figures 2, 3, 4 and 5 of the drawings, the holes 16 and 28, providing guides in applying the shingles in their different methods.

In Figure 2 a side lap method is illustrated in which the shingles are laid in rows with one straight edge 13 of one of the shingles overlapping the tab 9 of an adjacent shingle and underlying the flap 14 formed between the inclined cuts 8 and 12. In laying the shingles in this method the corner 15 serves as one guide for determining the extent of the lap while the guide hole 16 at the end of the slit 12 constitutes a stop for the edge 13, thus forming another guide therefor, the corner 15 and guide hole 16 being spaced inwardly from the edge of the flap 14 an equal distance to parallel the overlapping edges.

When laying the next succeeding row of shingles as shown at 17, the corner 18 of the cut-away portion 10 serves as a guide for the bottom edge of overlying shingles to determine the overlap, while the corner 9' of the tab 9 serves as a guide for the upper edge of the underlying shingle to likewise determine the overlap.

In the hexagonal method of laying the shingles as shown in Figure 3 of the drawings, the lower row of shingles are secured by copper clips or the like 19, or the shingles may be cemented, if desired, and the corners 20 and 21 constitute guides for the head lap for keeping the shingles in line by positioning said corners immediately above the edge of the adjacent underlying shingles. A guide hole 22, or notch, is also formed in one edge of the tab 9 to serve as a guide for the side lap of an overlying shingle, and a guide hole 28 for the same purpose is also formed adjacent another edge of the shingle.

The holes 16 are also used in a like manner for keeping the shingles true and straight on the roof and by means of these guide holes the

shingles may be laid left to right or right to left, as desired.

In Figure 4 I have illustrated the individual style of laying the shingles in which the lower 5 row of shingles designated at 23 are laid in edge-wise abutting relation, and the succeeding rows 24 are laid in a manner to overlie the abutting edges of the under row.

In Figure 5 I have illustrated the Dutch lap 10 method of laying the shingles and by means of which the lower row of shingles 25 are laid with the adjacent shingles in overlying relation with respect to the flap 14 and tab 9, and secured to the underlying shingle by copper clips 19, or 15 cemented, the corners 15 and the hole 16 constituting the guide to determine the side lap while the hole 28 and corner 9' constitute the guides for determining the head lap of the next succeeding row of shingles 26. Nail holes 27 may also 20 be formed in the tab 9 for securing the shingles in position, it being apparent that such nails are covered by the adjacent shingles, and in all methods of laying the shingles the same are blind-nailed at positions necessary so that none of the 25 nails are exposed.

It is believed the details of construction and manner of use of the invention will be readily understood from the foregoing without further detailed explanation.

Having thus described the invention, what I 30 claim is—

1. A composition shingle having right angular side edges, one of said side edges at one corner of the shingle having a substantially triangular shaped tab and one of the edges of the tab being partly separated from the shingle by a slit, said slit being adapted to receive the edge of an adjoining shingle to overlie the tab, the inner end of the slit constituting a stop to limit 35 the extent of the side lap, the other corner of

said one side edge being cut away diagonally and the ends of said cut-away portion constituting guides to also designate the extent of the side lap and the head lap of the adjoining and superposed shingles respectively. 5

2. A composition shingle having right angular side edges, one corner of the shingle having a tab projecting beyond one of the edges and an adjacent corner being cut away diagonally, the diagonal cut and one of the edges of the tab being 10 in parallelism to provide for the cutting of the shingles in matched pairs from a blank, said parallel cut of the tab merging with one of the side edges at an inclined angle and a slit extending inwardly of the shingle adjacent said point 15 of merger of the inclined edge of the tab, said slit being inclined in a direction toward an adjacent edge of the shingle and terminating in the body of the shingle short of said last named edge and cooperating at its inner terminus with 20 one end of the diagonally cut corner to indicate the extent of side lap with an adjoining shingle. 25

3. A composition shingle having right angular side edges, one corner of the shingle having a tab projecting beyond one of the edges and 30 an adjacent corner being cut away diagonally, the diagonal cut and one of the edges of the tab being in parallelism to provide for the cutting of the shingles in matched pairs from a blank, said parallel cut of the tab merging with one of the side edges at an inclined angle and a slit 35 extending inwardly of the shingle adjacent said point of merger of the inclined edge of the tab, said slit being inclined in a direction toward an adjacent edge of the shingle and terminating in the body of the shingle short of said last named edge, said inner terminus of the slit and one end of said diagonally cut corner being equidistant from the plane of said first named side edge. 40
